W. VAN HORN.
ROLL PAPER HOLDER AND CUTTER.

No. 448,097.

Patented Mar. 10, 1891.

UNITED STATES PATENT OFFICE.

WILLIAM VAN HORN, OF PIQUA, OHIO, ASSIGNOR TO CHARLES E. STUART,
OF SAME PLACE.

ROLL-PAPER HOLDER AND CUTTER.

SPECIFICATION forming part of Letters Patent No. 448,097, dated March 10, 1891.

Application filed February 9, 1888. Serial No. 263,434. (No model.)

To all whom it may concern:

Be it known that I, WILLIAM VAN HORN, a citizen of the United States, residing at Piqua, in the county of Miami and State of Ohio, have invented certain new and useful Improvements in Roll-Paper Holders and Cutters; and I do hereby declare the following to be a full, clear, and exact description of the invention, such as will enable others skilled in the art to which it appertains to make and use the same.

This invention relates to an improved roll-paper holder and cutter adapted to rest upon or be suspended below the counter of stores and other places, or rest upon a suitable support or be suspended in other desired positions, according to the use to which the holder and cutter is applied, be it for carrying wrapping or toilet paper.

In the drawings I have represented my invention as adapted for holding and cutting suitable lengths of wrapping-paper, though it is manifest that it may be equally well employed for holding and cutting off lengths of other paper.

The invention, briefly described, comprises a frame adapted to either rest upon a suitable support or be suspended in suitable position, and having vertical side pieces having grooved or recessed ways in their inner faces, a pair of roll-supporting slides contained and adapted to slide respectively within said ways, a pair of outwardly-curved pivotal arms, each connected, respectively, with one of said slides, and a knife connected at its respective ends to the lower ends of the pair of pivotal arms.

In the accompanying drawings, Figure 1 represents a front perspective view of my improved roll-paper holder and cutter, adapted to rest upon a counter, table, or other suitable support. Fig. 2 represents an end elevation thereof with a roll of paper in position therein. Fig. 3 represents a front elevation of the device adapted, as shown, to be suspended from a counter, shelf, or other support. Fig. 4 represents a perspective view of one of the side walls of the frame with one of the automatically-adjustable roll-supporting arms and one of the knife-carrying arms in position, the roll-supporting arms and the knife-carrying arms being shown in the position they

assume when a full or nearly full roll of paper is in the holder. Fig. 5 represents a similar view to Fig. 4, but showing the position those parts assume as the circumference of the roll diminishes by reason of the removal of paper therefrom. Figs. 6, 7, and 8 represent modifications in the mode of connection between the knife-supporting arms, frame, and roll-supporting arms.

In the construction as adapted to rest upon counters and the like, 1 represents the base-board or support for the roll-paper holder. This base-board is of sufficient size and weight to form a firm support and foundation for the holder when in use. It is designed to be made of sufficient breadth and thickness as to firmly and surely support the holder steadily while the paper is being unwound and cut off from the roll. It may either be made of wood or metal, as desired. The standards or side walls 2 of the frame have right-angled lower ends or feet 3, which are secured to the base 1 by screws, bolts, or other suitable means 4. By thus connecting the holder to such a base it can be readily shifted from one position to another upon a counter, as desired, and always supported rigidly in position without the necessity of securing it directly to and thereby defacing the counter.

Where, as shown in Fig. 3 of the drawings, it is desired to suspend the roll-paper holder from the under side of a counter, shelf, &c., 5, the base-board 1 is omitted and the respective standards 2 may in such case be formed of less length than is shown in Fig. 1—for instance, as represented in Fig. 3 of the drawings. Said standards 2 need not in such case extend below the top of the recessed or cut-away portion 6, while, however, it is preferable that in the hanging form shown in Fig. 3 the arms or standards 2 shall be thus shortened, as thereby the weight to be suspended will be decreased. Still it is not obligatory that said standards shall be thus shortened, as they may be of the same length in the hanging form as they are shown in Fig. 1.

7 represents a cap board or plate, which may be secured to the counter or shelf 5 by screws, bolts, or equivalent means for the purpose of suspending the holder in position. The standards 2 are preferably of metal,

- though they may be formed of wood. As clearly indicated in Fig. 1, they are made right and left, and have at their respective ends outturned flanges 3, by means of which 5 and the connecting screws or bolts they may be removably connected, respectively, to the cap 7 and base 1. Each of these standards 2 has in its inner face a vertical groove or guideway 9 to receive, and within which the roll- 10 shaft or spindle hangers or slides 10 are received and reciprocate. These roll-supporting slides or hangers 10 each have a hook-shaped lower end 11 to receive and support the roll-spindle 12. The slot or recess 6 in 15 the front edge of each of the standards 2 serves as a way through which the roll-spindle is introduced to its hook-shaped bearings 11 in the roll-supporting slides 10.
- 13 represents the knife-carrying arms. 20 They are of outwardly-curved shape, as shown, to permit of the free rotation of the paper-roll, and also to bring the knife 14 against the periphery of the roll of paper. These arms are connected at their lower ends by the 25 knife 14, which is either removably attached thereto by screws, bolts, or equivalent devices 15, as shown. If desired, however, either one or both of said arms 13 may be formed integrally with the knife 14, which latter need 30 simply consist of a flat or other suitably-shaped strip of metal, it not being necessary that the knife shall have a sharp cutting-edge. These knife-supporting arms are pivotally supported and connected at a suitable 35 point in their upper or rear portion either to the standards 2, as shown at 16 in Figs. 1, 2, 4, 5, 7, and 8 of the drawings, or else, as represented at 17 in Fig. 6, they are pivoted to the slides 10.
- 40 18 represents a curved slot formed in and extending transversely through the rear or upper portion of each of the arms 13, with which a lug or pin 19, projecting from either the roll-supporting slides 10 or the standards 45 2, engages. The object of thus pivotally supporting the knife-arms 13 and connecting them by slot 18 and pin or lug 19 either with the roll-supporting slides 10 or standards 2 is that upon the roll being placed in the slides 50 50 or carriers 10 its weight will pull down upon said slides or carriers, and this downward pressure causes the lug or pin which, as shown in Figs. 4 and 5, rests in the slot 18 to pull down on the knife-arms 13, thereby 55 bringing and retaining the knife 14 always in contact with the roll of paper, so that paper may be drawn from the roll and cut off by the lower edge of the knife and the loose end of the paper held in place.
- 60 60 When a full roll of paper is in the machine, the knife-arms 13 will stand in about the position shown in Figs. 2, 6, and 7, and the lug or pin 19 will occupy its nearest position to the pivots 16. In this position the downward 65 pressure at the knife 14 is least, but the weight of a full roll of paper supplies the desired amount of pressure. As the size of the

roll decreases the knife-arms gradually assume the position shown in Fig. 5, and the lug or pin 19 will occupy its farthest position 70 from the pivot 16. In this position the downward pressure at the knife 14 is greatest, but the decrease in the weight of the roll of paper decreases the pressure to about the desired amount. The curve in the slot 18 serves 75 to hold the knife 14 more firmly against the roll of paper as the downward pressure becomes more abrupt as the roll decreases in size. The guideways 9 prevent the hangers 10 from having a swinging motion, thus preventing the roll of paper from swinging away from the knife 14 when it is brought into contact with it by the downward pressure caused by the weight of the roll. The guideways 9 also by holding the hangers 10 in a perpendicular position, keep the lugs or pins 19 in proper position in the slots 18. Were it not for the guideways or their equivalent the lugs or pins 19 would fall to the lower end of the slots 18 at once, instead of coming to the position gradually as the size of the roll of paper decreases. This would give either too much tension on the knife in the start or else not enough in the end when the roll is small. 85 In Figs. 6, 7, and 8 slight modifications are 90 shown in the connection and operation of the knife-carrying arms 13. In Fig. 6 said arms are pivoted directly to the roll-carrying hangers or slides 10 and are pulled down directly by said hangers as they are pulled down by 95 the paper-roll, the movement of said arms 13 being regulated to maintain the knife 14 in contact with the paper-roll through the medium of the lugs or pins 19 on the standards 2 and the slots 18 in the rear of said arms in 100 the same manner as in the form illustrated 105 in Figs. 4 and 5. In Fig. 7 the same object is secured by pivoting the knife-arms 13 to the standards 2 and providing the roll-supporting slides 10 with a hook-shaped upper end 110 20. In this form as the slides are pulled down the arms 13 will be correspondingly drawn down to press the knife against the paper-roll.

In each of the forms illustrated in the 115 drawings the same results are secured—viz., the automatic gradual drawing down of the knife-carrying arms and the pressing of the knife against the paper as the circumference of the roll decreases and the widening of the 120 distance between the connections of said arms 13 with the slides 10 and of said arms 13 with the standards 2.

In lieu of forming grooves 9 in the inner faces of the standards 2, the manifest equivalent thereof of vertical ribs 21 may be formed on each side edge thereof, between which the slides 10 may be held and reciprocate, or, as represented in Fig. 8, the standards 2 may be formed with a vertical rib 22, extending a 125 short distance of its length, against which the front edge of the slide 10 may rest, and thus be held in perpendicular position, and the standards may be slotted, as shown at 23,

to receive the roll-spindle and retain it in position and prevent swinging motion of the roll.

Having thus fully described my invention, 5 what I claim is—

1. A roll-paper holder and cutter comprising a frame having standards or uprights having roll-receiving and slide-holding guideways therein, a pair of curved knife-carrying arms having pivotal bearing at their rear portion between said uprights, a knife attached to and connecting the front or lower ends of said arms, and a pair of slides loosely supported between and resting against the respective inner faces of the frame-standards and adapted to receive and support the paper-roll and engaging, respectively, with the knife-carrying arms, substantially as and for the purpose set forth.
2. A roll-paper holder and cutter comprising a framing having vertical guideways therein, a roller or spindle carrying the paper-roll, a pair of slides or hangers contained within said guideways with capacity of vertical reciprocation therein and adapted to support said roller-spindle and paper-roll, a knife, and a pair of outwardly-curved knife-carrying arms in contact with said slides or hangers and having pivotal bearing at their rear ends for the purpose of securing the automatic operation of said slides or hangers and knife-carrying arms and maintaining the knife in position against the paper-roll.
3. In a roll-paper holder, the combination of the standards 2, having vertical guideways therein, and roll-supporting hangers adapted to receive the roller-journals and suspend the paper-roll between and reciprocate vertically along said standards.
4. In a roll-paper holder, the combination of vertical standards having vertical guideways therein, roll-supporting hangers adapted to reciprocate along said guideways, a pair of pivotally-mounted knife-carrying arms connected to said roll-hangers and having a slotted rear portion, studs or pins engaging the slotted portions of said arms for the purpose

of maintaining the knife in position against the paper-roll, and a knife connecting said knife-arms together.

50

5. A roll-paper holder and cutter having a knife held to position against the roll of paper essentially by means of the weight of the roll, substantially as set forth.

6. In a roll-paper holder and cutter, the combination, with the paper-roll and its carrying roller or spindle, of a frame, a pair of slides adapted to receive said roller-spindle and to reciprocate vertically upon said frame, and a pair of knife-carrying arms having connection with said slides, whereby as said slides reciprocate said knife-arms will be either raised or lowered for the purpose of maintaining the knife in contact with the paper-roll, substantially as set forth.

65

7. A roll-paper holder and cutter having a pair of vertically-reciprocating roll-carrying slides, and a pair of knife-carrying arms connected therewith, whereby as said slides are drawn down by the weight of the paper said knife-arms will be correspondingly drawn down and the knife carried thereby pressed against the paper-roll.

70

8. A roll-paper holder and cutter comprising a frame having standards or uprights having vertical slots therein to receive the roll-spindle and vertical guideways to guide the roll-supporting slides and maintain them in position, a pair of curved knife-carrying arms having pivotal bearing at their rear between 80 said uprights, a knife attached to and connecting the front or lower ends of said arms, and a pair of slides supported between said standards with capability of vertical reciprocation therealong and adapted to receive and 85 support the paper-roll and engaging, respectively, with the knife-carrying arms, substantially as set forth.

In testimony whereof I affix my signature in presence of two witnesses.

WILLIAM VAN HORN.
